(57) **CLAIM**

We claim the ornamental design for a wall-mounted pendant enclosure for a spherical camera, as shown and described.

DESCRIPTION

FIG. 1 is a top perspective view of a wall-mounted pendant enclosure for a spherical camera;

FIG. 2 is a bottom perspective view thereof;

FIG. 3 is a front elevation view thereof;

FIG. 4 is a back elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines depict portions of a wall-mounted pendant enclosure for a spherical camera in which the design is embodied that form no part of the claimed design.
